UNITED STATES PATENT OFFICE.

MICHAEL ROSENBERG, OF CHELSEA, MASSACHUSETTS.

BELT-HOLDER FOR TROUSERS.

1,050,849.

Specification of Letters Patent. Patented Jan. 21, 1913.

Application filed September 5, 1912. Serial No. 718,604.

To all whom it may concern:

Be it known that I, MICHAEL ROSENBERG, a citizen of the United States, and resident of Chelsea, county of Suffolk, State of Massachusetts, have invented an Improvement in Belt-Holders for Trousers, of which the following description, in connection with the accompanying drawing, is a specification, like characters on the drawing representing

10 like parts.

This invention has for its object the production of a novel and efficient device for holding in proper position the waist-belt used by men for keeping the trousers in place, and my invention is so constructed that a convenient and strong attaching device is provided for the usual hook on the fly-lap of the garment.

One great objection to the use of waist-belts, particularly by large and stout men, is that the belt tends to slip upward at the front, so that the waist-band of the trousers will show more or less below the leather or other belt.

25 By my present invention the buckle of the belt is connected in a secure yet readily detachable manner with the waist-band portion of the trousers, completely obviating the foregoing objection and maintaining the belt at all times in proper position.

It is well known that the sheet-metal hook commonly used for holding the overlapping fly-flap in closed position is apt to work loose, for it is a difficult matter to attach it firmly and securely to the trousers.

35 In my present invention I make one member of the detachable or separable fastener for the belt serve also to secure the hook in position on the garment, so that it is impossible to loosen it while the cloth remains intact.

The novel features of my invention will be fully described in the subjoined specification and particularly pointed out in the following claims.

45 Figure 1 is a perspective view of the waist portion of a pair of trousers, with a waist belt, illustrating one embodiment of my invention the fly-flaps being opened and the belt loosened to show clearly the construction; Fig. 2 is an enlarged inner side view of the belt buckle, showing the tongue thereof provided with one member of the separable fastener; Fig. 3 is a front view of

fastener, the fabric of the garment being indicated by dotted lines; Fig. 4 is an enlarged sectional detail taken on the line 4—4, Fig. 1, through the shank of the hook and the coöperating member of the fastener; 60 Fig. 5 is a sectional detail on the line 5—5, Fig. 2.

Referring to Fig. 1, the upper or waist-band portion of a pair of trousers is indicated at 1, and the usual fly-flaps 2, 3 are shown as open, the flap 2 having attached to it a usual loop 4 for coöperation with the sheet metal hook 5, attached to the other flap 3. Herein I make the hook shank 6 flat and provide it with an aperture 7 through which is extended the tubular shank 8, Fig. 4, of a ball member 9 of the well known ball and socket type of separable fastener, the shank having the usual annularly enlarged base 10, and it is held in place 75 by the usual attaching washer 11.

In practice I insert the hook shank 6 between the inner and outer plies or thicknesses of fabric constituting the flap 3, and the shank is fixedly attached thereto by the 80 device just described and clearly shown in Fig. 4, the ball member 9 and the fastener being on the outside of the flap 3 and at the front of the garment, at the waistband portion thereof. If desired stitches may be 85 taken through the edge of the flap 3 and holes 12 provided for the purpose in the hook, to prevent any possibility of the displacement thereof, but it is to be understood that the main attaching device for the hook 90 is the fastener member and washer 11 above described, whereby the hook is so securely attached that it cannot be removed without taking a part of the garment with it.

The belt 13, of usual construction, is sustained by usual belt-loops 14 on the waist-band of the trousers, and said belt has a buckle 15 provided with a tongue 16, all of well known construction so far as described. In accordance with my present invention I 100 mount the second member of the fastener on said tongue, at the inner side thereof, and herein I have shown the socket member 17 of the fastener as attached to the tongue by a rivet 18. The rivet holds the member 17 105 rigidly in place on the tongue, at such a distance from its tip that the usual coöperation of the tongue with the perforated, free end of the belt will not be interfered with.

When the invention is in use the hook 5 110

is caught into the loop 4, retaining the fly-flaps overlapped and closed, and the belt is buckled up to the desired extent, the snapping of the ball member 9 into the socket member 17 of the fastener connecting the buckle and the trousers at the waistband part thereof. The belt is thus connected with the trousers so that it cannot slip up or down relatively to the trousers, but will 10 always stay in proper relationship thereto, just below the upper edge of the waistband.

Having fully described my invention, what I claim as new and desire to secure by Letters Patent is:

- 15 1. The combination with a pair of trousers having a hook connection for the fly-flaps at the waistband, and a detachable waist-belt having a buckle, of a hook-attaching device having at its outer end one member of a separable two-part fastener, and a coöperating member permanently attached
- 20

to the buckle at the inner side thereof, as and for the purpose set forth.

2. The combination with a pair of trousers having a hook on one flap, said hook having an apertured shank, and a waist-belt provided with a buckle having a tongue, of a ball and socket fastener to connect detachably said buckle tongue and the trousers, said fastener comprising a socket member 30 on the tongue at its inner side, and a co-operating ball member having a shank extended through the apertured shank of the hook, to attach the latter fixedly to the garment.

In testimony whereof, I have signed my name to this specification, in the presence of two subscribing witnesses.

MICHAEL ROSENBERG.
